United States Patent Office.

HENRY DIETZ, OF NEW YORK, N. Y.

Letters Patent No. 66,226, dated July 2, 1867.

STOVE FOR CARPENTERS' USE.

The Schedule referred to in these Letters Patent and making part of the same.

TO ALL WHOM IT MAY CONCERN:

Be it known that I, HENRY DIETZ, of New York, in the county and State of New York, have invented a new and useful "Improvement in Carpenters' Stoves;" and I do hereby declare that the following is a full and exact description of the same, reference being had to the accompanying drawings and to the letters of reference marked thereon.

Figure I represents a perspective elevation of my improved stove.

Figure II is a cross-section of the same.

The nature of this invention consists in the construction of a stove such as used by carpenters for the purpose of heating the glue and diverse pieces of wood to be glued in such a manner as to prevent all danger from fire arising from the breaking or cracking of the plates.

To a bottom plate, A, angle-irons *a* are securely fastened, to which are attached the upright pieces *b b*, likewise made of angle-iron, and on the top of which similar angle-iron pieces *c c* are attached, forming the frames of the stove. The space between the angle-irons is filled in by sheet-iron plates B riveted to the angle-irons. In the front plate a suitable opening is made for the fire-door. C is the pipe for the escape of the smoke. In the bottom of the stove, upon the plate A, fire-brick or soapstone D is placed as a lining for the purpose of preventing the burning through of the same.

By the expression "angle-irons" I mean wrought iron either rolled or bent in the shape of an angle, such as is commonly used in the manufacture of boilers. Carpenters' stoves at present are mostly made of cast iron, and it is consequently almost impossible to keep them tight, the heat bursting or cracking the sides in a very short time, and increasing therefore the danger of fire.

What I claim of my invention, and desire to secure by Letters Patent, is—

The construction of a carpenter's stove, by the combination of angle-irons and sheet iron, together with fire-brick or soapstone bottom lining, in the manner and for the purpose substantially as described.

HENRY DIETZ.
